RAILWAY TRAFFIC CONTROLLING APPARATUS

James J. Van Horn, Pittsburgh, Pa., assignor to
The Union Switch & Signal Company, Swiss-
vale, Pa., a corporation of Pennsylvania

Application May 8, 1943, Serial No. 486,190

6 Claims. (Cl. 246—3)

My invention relates to railway traffic controlling apparatus and more particularly to apparatus for the control of traffic in a single track, two-direction system wherein centralized traffic control or other suitable manual control is used for establishing the traffic direction. A distinguishing feature of my system is that it is of the normally deenergized coded track circuit type which dispenses with all control line wires except for the C. T. C. coded line circuit if C. T. C. control is used.

One object of my invention is to provide a normally deenergized track circuit system of signaling for traffic moving in either direction on a single track, employing no control line wires for the usual signaling functions. Another object of my invention is to provide signal control by means of track circuit code, employing master and feed-back codes for this purpose, the source of master code being located at one end only of the stretch. A further object of my invention is to provide an unoccupied block indication and a check of the stop indication of the opposing signal. A still further object is to prevent the removal of track circuit code while the stretch is occupied so that energy will be available for restoring the following stick relay to its normally deenergized condition, thus causing the track circuits to become normally deenergized.

I accomplish the foregoing objects by applying master code at one end of the stretch only, which causes the transmission of a feed-back code from the other end if the stretch is then unoccupied. Presence of these two codes makes it possible to clear the eastbound or the westbound headblock signal, as desired. By polarizing the feed-back code, an adequate unoccupied block indication for both ends of the stretch is provided. Also, by controlling the stick circuit of the relay which deenergizes the track circuits and which I shall designate a power-off relay over a back contact of the track relay repeater, it is possible to restore the stretch to its normally deenergized condition after the stretch is unoccupied, but not before.

I shall describe two forms of apparatus embodying my invention and shall then point out the novel features thereof in claims.

Fig. 1 of the accompanying drawings is a diagrammatic view showing a single track, two-direction signaling system embodying my invention and employing neutral feed-back code. Fig. 2 is a diagrammatic view showing a modified form of a portion of the system shown in Fig. 1, employing polarized feed-back code.

Similar reference characters refer to similar parts in each of the two views.

Referring to Fig. 1 of the drawings, I have shown a stretch of single track D—H divided into track circuit sections by means of the usual insulated rail joints at locations D, E, F, G and H. Location F is a cut-section location for the normally deenergized coded track circuits E—F and F—G. The normally energized short track circuits D—E and G—H at the respective headblock signal locations serve the usual detector function and permit following moves to be made either under a clear or a permissive signal indication.

At each end of the stretch is a field station unit connected with the usual C. T. C. line over which control impulses are sent out from a suitable C. T. C. control location or office, and over which the block unoccupied indication and the stop indication of the opposing signal are also transmitted from the field to the office. The C. T. C. apparatus, of itself, forms no part of my present invention and it is unnecessary to show this apparatus in detail for an understanding of my invention. Reference may be had to Letters Patent of the United States No. 2,229,249 granted to L. V. Lewis on January 21, 1941, for a detailed description of a C. T. C. system such as can be used herein and I have used the same reference numbers as are used in that patent to designate certain terminal wires of the field station unit which perform analogous functions.

The headblock signals 2 and 4 at the ends of the stretch control the entry of eastbound and westbound traffic respectively into the stretch, and the indications of these signals are controlled by means of track circuit codes which, in turn, are controlled by the field station C. T. C. apparatus. The master code which is applied at location G and is transmitted westwardly provides block control for signal 2, whereas the feed-back code which is applied at location E and is transmitted eastwardly provides block control for signal 4. The track circuits E—F and F—G become energized only after a suitable code is transmitted over the C. T. C. line to energize terminal 82 of the field station unit U2 or U4 in order to pick up the respective traffic control relay 2C or 4C, according as the traffic direction being established is eastbound or westbound.

The apparatus at the right-hand end of the stretch includes two signal control relays 4AD and 4BH, the first of which controls the upper unit of signal 4 whereas the second controls the lower unit of this signal, as indicated in the analogous control circuit for signal 2 in the draw-

ings. These two relays are controlled over a circuit which includes contacts of the detector track relay 4TR, directional stick relay 4SR, code checking relay 4TP, and the C. T. C. controlled traffic direction relay 4C or 4P, depending upon whether the operator desires to have signal 4 display a clear or a permissive indication, respectively. The relay 4SR is not shown in the drawings but is controlled in substantially the same manner as the relay 2SR.

The apparatus at the signal 4 location also includes the code selecting relay 4R which determines whether the track stretch will receive 180 or 75 master code, and it also includes the C. T. C. controlled normally deenergized power-governing relay PG which maintains code on the track circuits during such time only as required by traffic conditions. Relay CTM is the code repeating relay which applies master code to the track circuit F—G and relay 4T is the code following track relay which responds to feed-back applied at location F. Relay 4TP is a repeater of relay 4T and is maintained energized whenever the latter relay is following code.

As pointed out above, the power-off relay is C. T. C. controlled and is normally deenergized so that no code is applied to the track circuits until the operator sends out a code to pick up the relay PG so as to permit a train to enter the stretch. This code will be maintained effective during occupancy by means of a stick circuit for relay PG which includes the back contact 5 of relay 4TP and the front contact 6 of relay PG. The reason for including the back contact 5 in the stick circuit is to retain relay PG energized so that the operator cannot remove code from the track circuit during occupancy. Were such removal possible, track circuit energy would not be available for energizing the relays necessary for interrupting the stick circuit of the directional stick relay after a train vacated the stretch.

The apparatus at the west end of the stretch is generally similar to that at the east end except for the absence of code transmitters at this location and the presence of decoding apparatus which distinguishes between the two codes. The code transmitting relay at this location is the impulse relay 2BZ which transmits the feed-back code. The cut-section apparatus at location F includes the usual track relays and associated apparatus for repeating normal and feed-back codes over the cut-section location.

In explaining the operation, I shall assume that the stretch is in its normal, unoccupied condition so that the track circuits E—F and F—G are deenergized and the signals 2 and 4 are at stop. If the operator now wishes to display a clear aspect on signal 2 for an eastbound move, he will transmit a suitable code from the control office over the C. T. C. line so as to energize terminal 82 of the field station unit U2 and thereby pick up the eastbound clear control relay 2C. The operator will also send out a second code to the field station unit U4 at the other end of the stretch in order to energize terminal 84 so as to pick up the power-governing relay PG and so energize the track circuits by means of code. Pick-up of relay PG closes a circuit for each of the code transmitters 180CT and 15CT over the front contact 7, and also closes a circuit for relay 4R over the back contacts 8, 9 and 10 of relays 4SR, 4BH and 4AD, respectively. Since signal 4 is at stop, the signal control relays 4BH and 4AD will be deenergized. The directional stick relay 4SR will also be deenergized since the stretch is assumed

to be vacant. Accordingly, the energizing circuit for relay 4R will be closed and this relay will be picked up. Since the front point of contact 11 of relay 4R is closed, relay CTM will be coded at the 180 code rate over contact 12 of the code transmitter 180CT. Included in the circuit for relay CTM is the front contact 13 of track relay 4TR which prevents the application of code to the section, should a train be occupying the detector track circuit G—H.

If, instead of energizing relay 2C to cause the display of a clear indication by signal 2, the operator had energized terminal 81 of field unit U2, permissive control relay 2P would have been picked up so as to energize relay 2BH and thus cause the display of a permissive indication by this signal.

Relay CTM in following 180 code will cause current of this code to be periodically supplied from battery TB over the front point of contact 14 to the track circuit F—G. At location F track relay 4A will follow this code, being energized over the back point of contact 15 of the impulse relay 4AZ, and will repeat the code into track circuit E—F over the front point of its contact 16. Thereupon track relay 2T will also follow the code, being energized over the back point of contact 30 of relay 2BZ, and will energize the repeating relays 2BT and 2TP over obvious circuits. Relay 2BT is a slow acting relay which remains energized as long as relay 2T is following code, and relay 2TP is a code repeating relay which energizes the decoding transformer DT and its associated decoding equipment in the usual manner. In the case of long track circuits, the track relay 2T will ordinarily be a sensitive single-contact relay so that a repeater relay such as 2TP having the necessary number of contacts will be required. Relay 2BT will be energized only when relay 2T is following code. Consequently, front contact 17 will be closed and will apply energy to the decoding apparatus at such times only as code is present in the track section, in anticipation of the entry of a train. At all other times, the decoding apparatus will be deenergized to conserve power.

Since the track relay 2T is responding to 180 code under the assumed condition, both decoding relays H and D will be picked up. Relay H is picked up on either 180 or 75 code, whereas relay D responds only to 180 code because of the presence of the resonant rectifier unit 180DU in its energizing circuit. The pick-up of relay D, since relay 2C remains picked up over its stick circuit, closes the energizing circuit for the signal control relay 2AD which controls the clear indication of signal 2. The circuit for relay 2AD includes front contacts 18, 19 and 20 of relays 2TR, D and 2C, respectively, and back contacts 21 and 22 of relays 2SR and 2BH. Front contact 18 checks that the section D—E is unoccupied, whereas back contacts 21 and 22 check that the directional stick relay 2SR is released, as it should be when the stretch is vacant, and that signal 2 is not displaying a permissive indication.

Assuming for a moment that the stretch is occupied by an eastbound train, when the train enters the track circuit D—E the directional stick relay 2SR will be picked up over a circuit which includes the back contact 23 of relay 2TR and the front point of contact 24 of relay 2AD. A stick circuit for relay 2SR will now become effective over the back contact 25 of relay 2TR and the front contact 26 of relay 2SR. The latter relay, when energized, makes it possible

for the operator to transmit a control for displaying a permissive indication by signal 2 once the train has vacated section D-E.

Returning to the unoccupied condition of the stretch, since signal 2 is at stop relay 2RG is energized over a circuit which includes the back contacts 27, 28 and 29 of relays 2AD, 2BH and 2SR, respectively, and since relay 2TR is also energized, the circuit for impulse relay 2BZ will be closed so that this relay will be periodically energized from the decoding transformer in well-known manner and will operate contact 30 periodically to supply feed-back code over the front point of this contact to the track circuit E-F. This code is supplied during the "off" intervals in the normal or master code to which the relay 2T is responding, and operates the relay 2AT at the other end of the track circuit. Relay 2AT will follow the feed-back code and will maintain relay 2RGA energized so that the circuit for the impulse relay 4AZ will be closed at this time. Accordingly, relay 4AZ will transmit a feed-back code over the front point of its contact 15 and over the section F-G so as to produce code operation of relay 4T on feed-back code. Relay 4TP will therefore be energized.

Energization of relay 4TP indicates that the track stretch D-H between the signals 2 and 4 is unoccupied; that signal 2 is at stop; and that the directional stick relay 2SR is deenergized. Signal 4 may now be cleared. If, instead of causing signal 4 to display a clear indication, it is desired that this indication be a permissive one, the operator may cause relay 4BH to become energized over a circuit which includes front contact 31 of relay 4TP, back contact 32 of relay 4AD, and front contact 33 of the code controlled relay 4P which repeats the permissive position of the C. T. C. control lever (not shown) for signal 4 in the usual manner.

A westbound train accepting signal 4 and entering the track circuit G-H will cause the directional stick relay 4SR to become energized over a circuit similar to that shown and described for relay 2SR. Relay 4SR will thereafter remain energized over its stick circuit during occupancy of the section D-H.

With signal 4 displaying either a clear or a permissive indication, relay 4R will be deenergized because its circuit will be open at back contact 10 of relay 4AD or at back contact 9 of relay 4BH, respectively. Accordingly, 75 master code instead of 180 will be supplied to the track stretch over the back point of contact 11 of relay 4R. The track circuit apparatus in responding to 75 code will cause relay D at the west end of the stretch to become deenergized so that only relay H will now be energized. With relay D deenergized, signal 2 cannot display a clear proceed indication.

With signal 4 at stop and relay 4SR energized, relay 4R will be deenergized because its circuit will be open at back contact 8 of relay 4SR. Accordingly, 75 master code will be applied to the track stretch until the westbound train vacates the stretch whereupon feed-back code will be received from the west end to energize relay 4TP. The control network for relay 4SR is identical with that for relay 2SR at the other end with the exception that the back contact of relay D in the stick circuit is replaced by a back contact of the relay 4TP. Energization of relay 4TP will open the stick circuit of relay 4SR whereupon relay 4R will be energized to apply 180 master code to the stretch. Relay PG may

now be deenergized so as to deenergize the coded track circuit apparatus.

As long as master code is being applied at location G and the stretch remains unoccupied, one or the other of relays D and H will be energized so that an energizing circuit may be established for terminal 91 of the field station unit U2 to provide an unoccupied block indication. This circuit includes one or the other front contact 34 or 35 of relays H and D and is checked over front contact 36 of track relay 2TR. At the other end of the stretch, the clear block indication may be similarly obtained through the energization of terminal 91 of field station unit U4 over front contacts 37 and 41 of relays 4TP and 4TR. This, however, is not so satisfactory an unoccupied indication as that provided at the other end of the stretch because relay 4TP will be deenergized when signal 2 is cleared by means of the C. T. C. control, so that the occupied block indication will be given prior to the actual entry of a train into the section.

If it is desired to provide an unoccupied block indication at the east end which will be as satisfactory as that obtained at the west end, then the apparatus of Fig. 2 may be used. Referring to Fig. 2, the apparatus of this figure is similar to that of Fig. 1 with the exception that the feed-back code is now polarized. Accordingly, when relay 2RG which repeats the stop position of signal 2 is picked up, the feed-back code will be of normal polarity whereby relay 2ATA will operate its contacts to the left, as shown, and relay 2AT will respond to the impulses of feed-back energy supplied over the rails of section E-F. Relay 2AT is a biased polar relay which picks up on current of one polarity only, current of the other polarity causing its armature to be held firmly in the deenergized position. In this way, relay 2AT can be checked over the contacts of relay 2ATA to insure that the response of the latter relay is in agreement with the polarity of the feed-back code being supplied. If the feed-back code is of normal polarity, then relay 2RGA will be energized through the decoding transformer and over contact 38 of relay 2ATA closed in its left-hand position and will establish connections to cause impulses of feed-back energy of normal polarity to be supplied from the feed-back battery to the rails of section F-G as a result of operation of relay 4AZ. The feed-back energy of normal polarity supplied to the rails of section F-G causes the contacts of relay 4BTA to occupy their left-hand or normal position, so that on coding operation of relay 4BT energy is supplied through the decoding transformer to relay 4RGA and its contact 39 is picked up to establish a circuit leading to terminal 91 of the C. T. C. system field station unit and thus cause a block clear indication to be transmitted to the office.

When signal 2 displays a proceed aspect or the directional stick relay 2SR is energized, then relay 2RG will also be deenergized so that the feed-back code supplied to the rails of section E-F will be of reverse or negative polarity and will cause the contacts of relay 2ATA to occupy their right-hand or reverse positions so that on code following operation of relay 2AT energy is supplied from the decoding transformer over reverse or right-hand polar contact 38 of relay 2ATA to relay 2BP and its contacts are picked up. When relay 2BP is picked up, the feed-back battery is connected with the rails of track section F-G in such manner that on coding opera-

tion of relay 4AZ, impulses of feed-back energy of reverse polarity are supplied to the section rails. This feed-back energy causes the contacts of relay 4BTA to occupy their right-hand position so that on coding operation of relay 4BT energy is supplied from the decoding transformer to relay 4BP and its contact 40 establishes a circuit to energize terminal 91 of the C. T. C. system field station unit and cause it to transmit a block clear indication to the office.

The relay 4RGA employed in the modification shown in Fig. 2 may be substituted for the relay 4TP in the circuits of the relays 4AD, 4BH and PG in the system shown in Fig. 1. The relay 4RGA is deenergized when signal 2 is cleared or when the stretch is occupied and therefore insures that at these times relays 4AD and 4BH are both released to maintain the display of the stop indication by signal 4, while at these times relay 4RGA also maintains the stick circuit of relay PG to maintain the supply of track circuit energy to the track stretch. After signal 2 has been cleared, but while the stretch is still unoccupied, the relay 4BP is picked up to maintain the block clear indication.

From the foregoing, it will be apparent that the apparatus of Fig. 2 provides an unoccupied block indication at each end of the stretch which is independent of the indication which the entrance signal at that end may be displaying at the time.

Instead of employing C. T. C. or other remote control apparatus, it is apparent that direct manual control such, for example, as a signal lever at each end of the stretch may be used if desired to obtain the advantageous operation of the apparatus herein disclosed. In either case, the manual block signals will have full track circuit control thereof and will provide complete opposing signal protection. Since the signals themselves involve only safety circuits for their control, the auxiliary apparatus such as the C. T. C. equipment need not necessarily be of the safety type since this equipment merely supplements the signal control and provides for the transmission of the signal indications.

It will be apparent, also, that I have provided a normally deenergized coded track circuit system in which it is not necessary to cut off the track circuit energy at both ends of the stretch as in other systems, it being sufficient to cut off this energy at but one end in order to restore the system to its normally deenergized condition following the exit of a train. By polarizing the feed-back code, I provide an accurate unoccupied block indication at either end of the stretch.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a section of railway track over which traffic may move in either direction between the first and the second end thereof, a power-governing relay at the first end of said section having contacts movable between a first and a second position, means for at times moving the contacts of said power-governing relay from their first to their second position, means effective when the contacts of said power-governing relay are in their second position to cause master code energy to be supplied to the rails of said track

section at the first end thereof, means responsive to receipt of master code energy at the second end of said section for supplying impulses of feed-back energy to the rails of said section at the second end thereof, a signal governing entrance of traffic into said section at the first end thereof, and means responsive to receipt of feed-back energy over the section rails at the first end thereof for controlling said signal.

5 2. In combination, a section of railway track over which traffic may move in either direction between the first and the second end thereof, a power-governing relay at the first end of said section having contacts movable between a first and a second position, means for at times moving the contacts of said power-governing relay from their first to their second position, means effective when the contacts of said power-governing relay are in their second position to cause master code energy to be supplied to the rails of said track section at the first end thereof, means responsive to receipt of master code energy at the second end of said section for supplying impulses of feed-back energy to the rails of said section at the second end thereof, a signal governing entrance of traffic into said section at the first end thereof, means responsive to receipt of feed-back energy over the section rails at the first end thereof for controlling said signal, and means effective only when feed-back energy is being received at the first end of said section for moving the contacts of said power-governing relay from their second to their first position.

10 3. In combination, a section of railway track over which traffic may move in either direction between the first and the second end thereof, a power-governing relay at the first end of said section having contacts movable between a first and a second position, means for at times moving the contacts of said power-governing relay from their first to their second position, means effective when the contacts of said power-governing relay are in their second position to cause master code energy to be supplied to the rails of said track section at the first end thereof, means responsive to receipt of master code energy at the second end of said section for supplying impulses of feed-back energy to the rails of said section at the second end thereof, a first signal governing entrance of traffic into said section at the first end thereof, a second signal governing entrance of traffic into said section at the second end thereof, means responsive to receipt of master code energy over the section rails at the second end of said section for controlling said second signal, and means responsive to receipt of feed-back energy over the section rails at the first end thereof for controlling said first signal.

15 4. In combination, a section of railway track over which traffic may move in either direction between the first and the second end thereof, a power-governing relay at the first end of said section having contacts movable between a first and a second position, means for at times moving the contacts of said power-governing relay from their first to their second position, means effective when the contacts of said power-governing relay are in their second position to cause master code energy to be supplied to the rails of said track section at the first end thereof, a first signal governing entrance of traffic into said section at the first end thereof, a second signal governing entrance of traffic into said section at the second end thereof, means responsive to receipt of master code energy over the section rails at

the second end of said section for permitting said second signal to display a permissive indication, means responsive to receipt of master code energy over the section rails at the second end of said section provided said second signal is displaying its stop indication for supplying impulses of feed-back energy to the rails of said section at the second end thereof, and means responsive to receipt of feed-back energy over the section rails at the first end thereof for controlling said first signal.

5. In combination, a section of railway track over which traffic may move in either direction between the first and the second end thereof, a power-governing relay at the first end of said section having contacts movable between a first and a second position, means for at times moving the contacts of said power-governing relay from their first to their second position, means effective when the contacts of said power-governing relay are in their second position to cause master code energy to be supplied to the rails of said track section at the first end thereof, a first signal governing entrance of traffic into said section at the first end thereof, a second signal governing entrance of traffic into said section at the second end thereof, means responsive to receipt of master code energy over the section rails at the second end of said section for permitting said second signal to display a permissive indication, means responsive to receipt of master code energy over the section rails at the second end of the section for supplying to the rails of said section at the second end thereof impulses of feed-back energy

of a first or a second type according as said second signal is displaying its stop or a permissive indication, means responsive to receipt of feed-back energy of said first type only over the section rails at the first end thereof for controlling said first signal, and control means responsive to receipt of feed-back energy of either type over the section rails at the first end thereof.

6. In combination, a section of railway track over which traffic may move in either direction between the first and the second end thereof, a first signal governing entrance of traffic into said section at the first end thereof, a second signal governing entrance of traffic into said section at the second end thereof, means for supplying to the rails of said section at the first end thereof master code energy of a first or a second type according as said first signal is displaying its stop or a permissive indication, means responsive to receipt of master code energy over the rails of said section at the second end thereof and selectively responsive to the type of such energy for permitting said second signal to display a first or a second permissive indication according as said master code energy is of said first or said second type, means responsive to receipt of master code energy of either type over the section rails at the second end thereof for supplying impulses of feed-back energy to the section rails at the second end thereof, and means responsive to receipt of feed-back energy over the section rails at the first end thereof for controlling said first signal.

JAMES J. VAN HORN.
